UNITED STATES PATENT OFFICE

AUGUSTUS D. BOOTH, OF COLUMBUS, OHIO, ASSIGNOR TO THE CHASE FOUNDRY AND MFG. COMPANY, OF COLUMBUS, OHIO, A CORPORATION OF OHIO

COUPLER

Application filed June 11, 1930. Serial No. 460,383.

This invention relates to improvements in couplers for use in connection with industrial cars, trailer trucks and is well adapted for general use where an automatic coupler is desired.

It is particularly the object of this invention to provide a coupler having an upper and a lower jaw pivoted to the main coupler frame so that each jaw may move upward thereby allowing for and providing flexibility in the draw bar pull when passing over inclines, ramps and other irregular surfaces.

It is also an object of this invention to provide in connection with one of these jaws, means by which one car may be attached to another to constitute a train of cars. This attachment is effected automatically by simply bringing the coacting part of the coupling members in contact with each other, whereby one of the pivoted jaw members moves so that coupling is effected.

These and other objects and advantages will appear from the description taken in connection with the drawings.

Referring to the drawings:

Figure 1 is a top plan view of the coupler. Figure 2 is a side elevation of the coupler.

Figure 3 is a longitudinal section through a coupler with the upper jaw elevated.

Figure 4 is an end elevation with the upper jaw elevated.

Figure 5 is a longitudinal sectional view showing both jaws in elevated position.

Figure 6 is a longitudinal sectional view showing the jaws in engagement with each other in their normal position.

The main part of the coupler consists of a head having a base 1 and two parallel side walls 2 constituting a housing supporting one of the ends of each of the coupler jaws. Between the two side walls and near the upper end of the base is a stop shoulder 3. In each side wall is an upper bearing 4 and a lower bearing 5 to receive shafts that support the jaws. The upper jaw is indicated by the numeral 6 and has on one end a bearing 7.

Through this bearing 7 and the upper bearings in the side walls a shaft 8 extends. This shaft is held in position by any suitable means. In the present instance cotter pins

are used in holes in each end of the shaft. On the end of the upper jaw adjacent the bearing is a stop arm 9 adapted to engage the stop shoulder 3 when the upper jaw is swung to its uppermost position.

At the front end of the upper jaw there is provided a hook 10 which extends downwardly in the direction of the head. This hook provides means for engaging a link, or some suitable means, on a truck or another car similar to the one to which this coupler is attached. The front end of the jaw and the hook are provided with an inclined face 11 which directs the link or other coupling member down toward the lower end of the hook so that this jaw may raise and the member engage with the hook 10 for connecting two cars or one car to a truck. To the rear of the hook is a stop 12 extending downwardly from the upper jaw 6 at substantially a right angle to the body of the jaw. This stop serves to limit the backward movement of the coupling member that co-acts with the hook 10.

Beneath the upper jaw is a lower jaw 13 having a bearing 14 at one end. Extending through the bearing 14 and the lower bearings of the two side walls is a shaft 15 which supports the jaw pivotally between the side walls. This shaft is held in place by means of cotter pins, but other suitable means may be used. The outer end of this jaw is downwardly inclined at 16, and has a surface coacting with the surface 11 to direct the coacting coupling member so that it may pass between the two jaws and engage behind the hook 10.

For the purpose of providing a seat for the lower ends of the hook member 10 and the stop 12, the upper side of the lower jaw is provided with a recess 17. The walls of this recess serve also to hold the cooperating coupling member in engagement with the hook 10 so that it cannot become easily disengaged therefrom. For the purpose of accommodating and providing free space for the cooperating coupling member the ends of the side walls remote from the base are provided with notches 18. When the cooperating coupling member is in place it is with-

in these notches and between the hook 10 and the stop 12. For the purpose of supporting the lower jaw 13 in its normal position there is provided between the two sides a stop 20, 5 upon which this lower jaw rests when in normal position. When the lower jaw is thus supported on the stop 20 it is substantially in line with the body of the truck to which the coupler is attached.

10 If the lower jaw should contact with any surface so that it would be necessary that this jaw be elevated the two jaws may be swung upward to the position shown in Figure 5. In this instance both jaws move together. However, the upper jaw may move independent of the lower jaw. This would especially occur when the front car is going up an incline even though the lower jaw behind touch the inclined surface. However, if 15 the incline were sufficiently steep the front part of the lower jaw may contact with the inclined surface, in which event the lower jaw would be forced upward in the direction of the upper jaw.

20 By means of the coupler here shown two trucks or cars may be attached to each other automatically by merely forcing the other coupling member into contact with the inclined surfaces 16 and 11 so that the other coupling member will raise the upper jaw and engage behind the hook 10. In order to release the coupler it is only necessary to raise the upper jaw, when the cooperating coupling member may be removed.

25 I desire to comprehend within my invention such modifications as may be clearly embraced within my claims and the scope of my invention.

Having thus fully described my invention, 30 what I claim is new and desire to secure by Letters Patent, is:

1. In a coupler, a head member, a coupler jaw having a coupler hook thereon supported by the head for vertical movement, and a 35 second jaw supported by the head for vertical movement, said second jaw having a recess therein adapted to receive and partly support the coupler hook.

2. In a coupler, a head member, a coupler jaw having a coupler hook and a stop thereon supported by the head for vertical movement, and a second jaw supported by the head for vertical movement, said second jaw having a recess therein adapted to receive and partly 55 support the coupler hook and the stop.

3. In a coupler, a head member consisting of a base and side walls, and a pair of cooperating jaws pivoted to and supported by said side walls in a substantially horizontal 60 position so that both jaws may be moved upward together from said position but only one can be moved independent of the other.

4. In a coupler, a head member consisting of a base and side walls, a pair of cooperating 65 jaws pivoted to and supported by said side

walls in a substantially horizontal position so that both jaws may be moved upward together from said position but only one can be moved independent of the other, and means to limit the movement of said jaws. 70

5. In a coupler, a head member consisting of a base and side walls, said base having a stop, a recessed jaw pivoted to and supported by said walls in one position and a second jaw pivoted to the side walls and having a hook and a stop, said last stop adapted to engage in the first stop, said second jaw being supported in one position by the hook resting on the first-named jaw in the recess thereof, said jaws having oppositely flared outer ends to receive a coupling member for engaging the hook. 75

6. In a coupler, a head having a pair of spaced parallel walls having an upper and a lower stop, a recessed jaw pivoted to said walls and supported in one position by, said lower stop and a second jaw pivoted to said walls and having a hook and a stop, said stop adapted to engage the upper stop and the hook adapted to engage the recessed arm in the recess thereof so that both arms may be moved up together but only one arm be so moved independent of the other, the outer end of the recessed jaw and the hook forming an inclined surface leading obliquely toward the second jaw and the upper stop limiting the upward movement of one or both jaws. 80

7. In a coupler, a head member consisting of a base and side walls, a recessed jaw pivoted to said side walls, means on the head member to prevent the jaw swinging down, and a second jaw pivoted to said walls and having a hook thereon adapted to rest in the recessed jaw to support the second jaw. 85

8. In a coupler, a head member consisting of a base and side walls, a recessed jaw pivoted to said walls, means on the head member to prevent said jaw swinging down, a second jaw pivoted to said walls and having a hook thereon adapted to rest in the recessed jaw to support the second jaw, and stop means on the head member and the second jaw to limit the upward swinging of the second jaw. 90

In testimony whereof, I affix my signature.

AUGUSTUS D. BOOTH.
